SHEET HOLDER FOR MATTRESS
ENSEMBLES

Warren W. Rosing, Buffalo, N. Y.

Application June 8, 1951, Serial No. 230,447

8 Claims. (Cl. 5—320)

1

This invention relates to improvements in mattress ensembles, that is to say, a combination which consists of a mattress and a supporting element upon which the mattress rests, the supporting element being a box spring or a rigid supporting frame resting upon, and freely removable from, flanges or shoulders provided upon the side rails of the bedstead. The invention is directed to a mattress ensemble which includes as a permanent part thereof a novel and advantageous bottom sheet holding feature carried by and in cooperation with the supporting element.

Broadly speaking mattress ensembles are of two types, one in which the mattress is freely removable from the supporting element and the other in which the ensemble is unitary in that the mattress is permanently connected to the supporting element. Ensembles of the unitary type include a form which has a box spring and in which the lines of connection between the mattress and the top fabric of the box spring are several inches distant from their sides and ends, thereby leaving their marginal portions in unattached relation in order to provide intervening marginal recesses. Ensembles of the unitary type also include other forms which utilize a box spring or a rigid supporting frame and in which the marginal recesses are not provided, the mattress and its supporting element being enclosed within a tightly fitted fabric casing.

In making the bed it is desirable, as a matter of neat and attractive appearance and also as a matter of comfort in use, that the bottom sheet as laid upon the mattress be smooth and, with its four corners "mitered," that its projecting side portions be held by the ensemble, thereby to maintain the sheet under tension and against free displacement.

In the construction in which the mattress is freely removable the practice is to tuck the extending portions of the bottom sheet between the adjacent faces of the side marginal portions of the mattress and its supporting element. In this case the weight of the mattress is relied upon to hold the bottom sheet. In the unitary construction in which the marginal recesses are provided the marginal portions of the mattress and the box spring have a certain measure of resiliency and thereby tend to press firmly against one another and to close the recesses; and the practice is to tuck the bottom sheet into the marginal recesses at the sides of the ensemble. In this case the marginal portions of the mattress and the box spring tend to seize the tucked-in parts of

2

the bottom sheet and hold them with frictional clamping pressure.

Due to the necessity of tucking the bottom sheet between the mattress and its supporting element or within the marginal recesses provided by the mattress and the box spring the work of properly making the bed requires an undue amount of time and care and is quite laborious and tiring since in tucking in the bottom sheet 5 the effort is opposed by the weight of the mattress or by the resiliency of the parts of the mattress and the box spring which provide the walls of the marginal recesses, it being borne in mind that this work must be so performed as to effect 10 the tensioning of the bottom sheet and to avoid disturbing the smoothness of the sheets and blankets. In many cases the pressure with which the sheet is held is not sufficient to prevent displacement of the sheet when the occupant of 15 the bed shifts his position from time to time.

In the unitary type wherein the marginal recesses are not provided the only way in which the bottom sheet can be held against displacement is by the use of pins engaged with the fabric covering; this is objectional both as being unduly 20 laborious and because of the liability of tearing the sheets and blankets or the covering of the mattress ensemble, particularly in connection with changes of sleeping or resting positions by 25 the occupant of the bed.

The object of the invention is to provide a bottom sheet holder of novel and advantageous construction as a permanent part of a mattress ensemble of any of the forms above described and 30 which is carried by and in cooperation with the mattress supporting element. The novel construction of the holder and its novel relation in and as a part of the mattress ensemble achieve advantages as follows, viz., substantial reduction 35 in both the time and labor which has been heretofore required in securing the bottom sheet; a substantially more effective retention of the bottom sheet, minimizing the liability of its displacement in consequence of changes of position by 40 the occupant of the bed; structural simplicity; a neat and attractive in appearance; and economy of production and application in connection with the manufacture of the ensemble.

The forms selected for illustration are mattress ensembles of the unitary type wherein the mattress and its supporting element are enclosed within a fabric casing.

In the drawings:

Figure 1 is a perspective view of a mattress ensemble in accordance with the invention, this

view being applicable to either of the forms of the supporting element as above generally described and showing a preferred construction of the bottom sheet holding feature.

Figure 2 is a fragmentary cross sectional view showing a mattress ensemble in which the supporting element is a box spring, the section being taken on the line 2—2 of Figure 1.

Figure 3 is a fragmentary sectional view on the line 3—3 of Figure 2, this figure showing one of the flexible stays for the fabric part of the holder.

Figure 4 is a detail cross sectional view on the line 4—4 of Figure 3.

Figure 5 is a fragmentary elevational view looking at the inner face of the bottom sheet holder and showing details of the connections between adjacent end edges of the attached fabric part of the holder.

Figure 6 is a fragmentary perspective view of the ensemble showing the manner in which the bottom sheet is secured by the holder.

Figure 7 is a fragmentary cross sectional view showing an alternative form of mattress structure.

Figure 8 is a fragmentary cross sectional view showing another alternative form of mattress structure.

Figure 9 is a fragmentary cross sectional view showing a mattress ensemble in which the supporting element is a rigid frame, the section being taken on the line 2—2 of Figure 1.

Figures 10 to 13 show a modified construction of the bottom sheet holding feature.

Figure 10 is a perspective view of a mattress ensemble in accordance with the invention in which the modified construction of bottom sheet holding feature is incorporated.

Figure 11 is a fragmentary horizontal section on the line 11—11 of Figure 10.

Figure 12 is a fragmentary sectional view on the line 12—12 of Figure 11.

Figure 13 is a fragmentary sectional view similar to Figure 12 but showing the ensemble in accordance with the construction shown in Figure 9 wherein the mattress supporting element is a rigid frame.

The mattress 1 may be of any desired known construction. Figures 2 and 9 show a mattress composed of an appropriate number of layers 2 of felted material e. g. cotton. Figure 7 shows a spring mattress having the usual covering 3 composed of a suitable number of relatively thin layers of felted material. Figure 8 shows a mattress composed of resilient material 4 such as foam rubber.

The mattress supporting element 5 may be a box spring 6 (Figure 2) having at its upper side the usual wear and noise preventing elements 7 against which the springs 8 react and upon which the mattress 1 rests and having the usual bottom frame 9 which is preferably composed of wooden parts. Alternatively the mattress supporting element may be a rigid frame 10 (Figure 9), economically made of wood, which includes vertical side and end walls 11 and cross slats 12 or mechanically equivalent parts extending between the side walls and suitably secured to their upper faces, the slats 12 or their mechanical equivalents being the parts upon which the mattress 1 rests.

In the forms selected for illustration the mattress 1 and its supporting element 5 are enclosed within a tight fitting cover 13 of suitable fabric, the lower edges of which are inturned under and

secured to the supporting element 5. In the construction shown in Figure 2 the inturned lower edges of the cover 13 are secured to the frame 9 and in the construction shown in Figure 9 they are secured to the lower faces of the vertical walls 11. The cover 13 as thus secured aids in maintaining the unitary assembly of the mattress and the supporting element.

The bottom sheet holder is so combined with the supporting element 5 as to provide an external pocket 14 preferably substantially lineally coextensive with the vertical walls of the supporting element, these walls being the inner walls of the pocket 14. The pocket is completed, that is to say its outer walls are provided, by a strip 15 of suitable fabric which in the construction preferred circumscribes the supporting element and is yieldably maintained in adjacent relation to its outer vertical faces and in the modified construction, later described, extends lineally along the side and lower end walls of the supporting element and is yieldably maintained in adjacent relation to their outer vertical faces. The lower edge portion of the strip 15 is attached throughout the lineal extent of the strip to the lower portion of the supporting element, its attached portion providing a closed bottom for the pocket 14. In the construction shown in Figure 2 the lower portions of the strip 15 are turned under the element 5 and secured to the frame 9 and in the construction shown in Figure 9 they are turned under the vertical walls 11 and secured to their lower faces. The same fasteners may be used for securing both the cover 13 and the strip 15. The vertical extent of the strip 15 is such that the pocket 14 is of ample depth for the reception in flat relation of the marginal portions of the bottom sheet.

Except for the attachment of its lower portions the strip 15 is free relatively to the supporting element. According to the invention the strip 15 carries near its upper edge an elastic band 16 for applying frictional clamping pressure to the bottom sheet. In the preferred construction the band 16 encircles the mattress supporting element 5, extending adjacent its outer vertical faces. The element 5 maintains the band 16 under tension and the band 16, as so maintained under tension, is substantially lineally coextensive with the strip 15. In making the bed the upper portion of the strip 15 is pulled outwardly or laterally away from the supporting element 5 at various successive points along its extent, thereby in each operation to open the pocket 14 through an appropriate lineal extent and permit the arrangement within it of the hanging portions of the bottom sheet. The strip 15 may be manipulated in this manner because its terminal vertical edges 19 are free relatively to the supporting element 5 and hence its terminal portions are free to yield relatively to one another when the strip 15 is pulled away from the supporting element 5. When that portion of the strip 15 which has been pulled away from the supporting element 5 is released it is brought back by the band 16 into adjoining relation to the opposing face of the supporting element 5; and when the manipulation of the strip 15 is completed, i. e. when the bed has been made, the free terminal portions of the strip are returned to their original relation in which the strip is held flat. This return to their original relation of the free terminal portions of the strip may be effected by elastic connections, later described in detail. Thus the inner walls of the pocket 14 which are provided by the supporting element 5 are rela-

tively fixed and the outer walls which are provided by the strip 15 are flexible and yieldable.

In the construction preferred the band 16 is endless. A rubber band is shown as a practical example but it will be understood that other well known forms may be used such as a band of elastic fabric or a coiled spring band of small diameter. The band 16 may be associated with the strip 15 in any suitable manner and the pocket 14 extends a substantial distance below the band and is therefore relatively deep. As shown the upper portion of the strip 15 is of two-ply construction (Figure 4), the inner ply 17 being preferably integral with the strip 15 and inturned adjacent the inner side of the pocket; and the plies are secured together by stitching which is so arranged as to provide near the lower edge of the inner ply a sheath 18 lineally coextensive with the strip 15, the walls of the sheath being provided by the plies. The band 16 is loosely fitted in the sheath 18 which thereby provides a means of operative connection between the band 16 and the strip 15 and permits relative sliding movement of the band and the strip when the strip, during the making of the bed, as later described in detail, is pulled away from the mattress supporting element 5. In the preferred construction wherein the strip 15 substantially circumscribes the supporting element 5 its end edges 19 (Figure 5) are closely adjacent and may, for convenience, be referred to as "meeting" edges although they do not necessarily meet in a literal sense. In this construction the adjacent free terminal portions of the strip 15 are connected by tensioned elastic means such, for example, as one or more short transverse strips 20 of elastic fabric which extend across the space between the edges 19 and at their ends are secured to the strip 15 at points suitably adjacent the edges 19. The ends of the sheath 18 are open and the band 16 extends across the space between the edges 19.

The strip 15 is preferably provided along its upper edge with a continuous bead 21 which, in addition to having an ornamental quality, enables the upper edge portion of the strip to be readily grasped and pulled away from the cover 13 when portions of the bottom sheet are to be inserted into the pocket 14. The bead 21 is composed of a strip of suitable fabric, being bent upon itself with its plies secured by stitching to the inner ply 17 and the bead 21 projecting upwardly to a suitable extent beyond the upper edge of the strip 15.

The elastic band 16 is ideally positioned with its axis in a horizontal plane prescribed by the vertical extent of the strip 15 and parallel to the horizontal plane of the supporting surface of the mattress 1. Thereby the pocket 14 is maintained at its maximum depth and the retaining pressure exercised by the band 16 is uniform throughout the lineal extent of the band. In order that this relation may be positively maintained it is preferable to employ in association with the strip 15 a suitable number of flexible and resilient vertical stays 22 which may be arranged at desired intervals along the sides and ends of the ensemble. These stays may be economically provided as flat flexible strips of plastic material which due to their resilience tend to occupy true normal planes and are unyielding from edge to edge and from end to end but which may be readily flexed along any transverse line and in either direction from their normal planes. The stays 22 are preferably secured to the strip 75

15 in the manner and relation shown in the drawing (Figure 4). Thus they are arranged adjacent the inner faces of the strip 15 and their upper portions project into the sheath 18, being located behind the band 16, that is to say between the band 16 and the strip 15, and being secured by one of the lines of stitching which secures the ply 17 to the strip 15 and delimits the sheath 18. The stays 22 project downward from the sheath 18 and at their lower ends react against the inturned lower portions of the strip 15, the stays 22 being bent under and suitably attached to the supporting element, for example, by the same fasteners which secure the strip 15. Any tendency during the insertion of parts of the bottom sheet into the pocket 14 toward downward displacement of the band 16 is compensated by the stays 22 which react against the bottom of the pocket 14 while at the same time these stays, due to their flexibility, will oppose no appreciable resistance when the strip 15 is pulled away from the cover 13 or when it is drawn toward the cover by the elastic action of the strips 20.

In order that the ensemble may be conveniently lifted from the bedstead bails or hand grips 23, are provided in accordance with the usual practice. These, however, are attached to the outer faces of the strip 15 at the sides of the ensemble.

Figure 6 shows the manner in which the bottom sheet S is fitted and secured in the pocket 14. This figure shows the sheet mitered as at M at one of its lower corners and with its pendant sides and lower end portion inserted into the pocket 14. As thus inserted the sheet will be firmly held by the band 16 which exercises suitable retaining pressure due to the fact that it is maintained under tension by the mattress supporting element. In effect the portions of the sheet within the pocket 14 are frictionally clamped by the band 16 in cooperation with the adjacent vertical faces of the mattress supporting element. When the sheet is to be inserted into the pocket 14 the upper portion of the strip 15 is grasped and, together with the band 16, pulled away from the adjacent vertical face of the mattress supporting element, thereby opening the pocket 14 to a suitable extent. This action is permitted by the loose fit of the band 16 in the sheath 18 whereby when the strip 15 is pulled away from the mattress supporting element the band and the strip are relatively slid able. It is also permitted by the elastic connections 20 which yield or stretch when the strip 15 is pulled away from the mattress supporting element and draw the meeting edges 19 together when the manual pull upon the upper portion of the strip 15 is released. The stays 22 will of course yield or flex when the strip is thus pulled away from the mattress supporting element. When the strip 15 is released the band 16 springs back into its functional position in which it closes the pocket 14 and exercises retaining pressure upon the sheet; the strip 15, maintained under pulling stress by the elastic connections 20 is brought back by these connections into adjacent relation to the walls of the supporting element, that is to say its edges are drawn together since the strip may slide relatively to the band 16 which is loosely fitted in the sheath 18; and the stays 22 spring back into their normal true planes in which they are straight and substantially vertical and will thereby hold the strip 15 fully extended in the vertical direction and insure that the band 16 is positioned with its axis in a horizontal plane

prescribed by the vertical extent of the strip 15 and parallel to the horizontal plane of the supporting surface of the mattress 1.

Referring to Figures 10 to 13:

These figures illustrate a modification in which the essential distinguishing features of construction and operation as above described are incorporated but wherein the strip, here designated 15a, which provides the pocket 14, does not completely circumscribe the mattress supporting element but instead adjoins its side walls and foot wall. In this construction, therefore, the strip 15a does not have meeting end edges such as the edges 19 of the strip 15. The connections 20 of the preferred construction have their equivalent in the modified construction in elastic connections 20a which are preferably of elastic fabric and are attached to the free terminal portions of the strip 15a and to the supporting element 5. The points at which the connections 20a are attached to the element 5 may be at the rear ends of its side walls but are preferably, as shown, at the outer ends of its upper or head end wall. The attachment of the connections 20a to the supporting element 5 is preferably effected by detachable fasteners. In the construction shown in Figures 10, 11 and 12 which assume that the mattress supporting element is a box spring these fasteners, shown at 24, may conveniently be of the ball and socket type with the socket elements carried by the connections 20a and the ball elements carried by the fabric cover of the ensemble. In the construction shown in Figure 13 which assumes that the mattress supporting element is a rigid frame, such as is shown in Figure 9, the fasteners may be tacks 24a which are readily removable and have their shanks driven into the adjacent wall of the supporting element.

In the modified construction the tensioned band, here designated 16a, which exercises clamping pressure upon the bottom sheet is preferably of elastic fabric and is fitted in a sheath of the construction above described. The modified construction follows the preferred construction by having the band 16a loosely fitted in the sheath, thereby to permit a relative sliding movement between it and the strip 15a. Accordingly the ends of the band 16a project beyond the ends of the sheath and are attached, as by stitching, to the connections 20a. Each of the strips of elastic fabric which provide these connections is preferably bent upon itself to provide an extension 20b to which the ends of the band 16a are attached.

The detachable fastenings for the attachment of the connections 20a to the supporting element 5 enable the ready disconnection of the ends of the strip 15a in the event that it be desired to replace a worn band 16a by a new one.

The modified construction is otherwise similar to the preferred construction above described and has the same operative characteristics, both in respect to the making of the bed and the retention of the bottom sheet when the bed is made.

The holding of the marginal portions of the bottom sheet as above described is a matter of necessity when the bed is properly made. Whether the top sheet or a blanket or blankets used as body covering be similarly held is a matter of choice on the part of the individual who makes the bed. Therefore, if so desired, the top sheet and the blanket or blankets laid over the top sheet may be similarly held by the bottom sheet holding feature as herein described although in such a case the top sheet and the

blanket or blankets should be mitered separately from the bottom sheet since they must be freed, without disturbing the bottom sheet, from the bottom sheet holding means when the bed is to be occupied.

I claim:

1. A mattress ensemble consisting of a mattress, a supporting element upon which the mattress rests and bottom sheet holding means carried by and cooperating with the mattress supporting element, such means comprising a strip of fabric extending adjacent the sides and at least one end of the supporting element and having its lower edge portion attached to the supporting element adjacent its bottom, the strip cooperating with the adjacent vertical faces of the supporting element to provide a continuous externally located pocket for the reception of the pendant parts of the sheet and of a depth in which said parts may be fitted in flat relation with mitered corners, the strip providing flexible outer walls of the pocket and the vertical faces of the mattress supporting element adjacent the strip providing fixed inner walls of the pocket, the lower edge portion of the strip as attached to the supporting element providing a closed bottom for the pocket, a band of elastic material carried by the strip near its upper edge and normally positioned with its axis in a horizontal plane parallel to the plane of the supporting surface of the mattress, the band being adjacent the vertical faces of the supporting element opposed to the strip and being maintained under tension by the supporting element, the band as maintained under tension by the supporting element being substantially lineally coextensive with the strip, the strip being provided with a continuous sheath open at its ends and in which the band is loosely fitted, the strip and the band being manually pulled laterally away from the supporting element to open the pocket to a suitable extent for the insertion of the pendant parts of the sheet, the strip and the band having a relative sliding action when they are pulled laterally away from the supporting element, the strip having terminal portions which yield relatively to one another when the strip and the band are pulled away from the supporting element, and elastic means so connected to the terminal portions of the strip as to maintain the strip normally in flat relation adjacent the vertical faces of the supporting element opposed to the strip, the band at such time being in adjoining relation to the pendant parts of the sheet within the pocket and cooperating with the adjacent vertical faces of the supporting element in exercising retaining pressure upon such parts, said elastic means serving to return the strip to its normal flat relation adjacent the vertical faces of the pocket when the strip is finally released after being pulled away from the supporting element in connection with the making of the bed.

2. A mattress ensemble as set forth in claim 1 wherein the sheet holding means includes flexible and resilient vertical stays which are fixed to the strip at their upper ends and which tend to occupy true planes, the lower ends of the stays adjoining and reacting against the closed bottom of the pocket and the stays serving to maintain the vertical extension of the strip and to maintain the band with its axis in a horizontal plane parallel to the supporting surface of the mattress.

3. A mattress ensemble as set forth in claim 1 wherein the upper portion of the strip is of two-ply construction with the inner ply attached to

the rest of the strip by lines of stitching, portions of the plies between said lines forming the walls of said sheath.

4. A mattress ensemble as set forth in claim 1 wherein the upper portion of the strip is of two-ply construction with the inner ply attached to the rest of the strip by lines of stitching, portions of the plies between said lines forming the walls of said sheath, and the sheet holding means includes flexible and resilient vertical stays which tend to occupy true planes, the upper portions of the stays being inserted into the sheath behind the band and secured by the stitching which connects the plies and the lower ends of the stays adjoining and reacting against the closed bottom of the pocket, the stays serving to maintain the vertical extension of the strip and to maintain the band with its axis in a horizontal plane parallel to the supporting surface of the mattress.

5. A mattress ensemble as set forth in claim 1 wherein the fabric strip substantially circumscribes the mattress supporting element and has its end edges in substantially meeting relation, the band of elastic material is endless and the elastic means comprises strips of elastic material connected to the portions of the strip which adjoin the substantially meeting edges and extending across the space between such edges.

6. A mattress ensemble as set forth in claim 1 wherein the fabric strip extends adjacent the sides and but one of the ends of the supporting element, the ends of the strip are connected to the supporting element adjacent the other end thereof, the elastic means connected to the ends of the strip serves for the connection of the ends of the strip to the supporting element and consists of strips of elastic material which are also connected to the supporting element, and the band has projecting end portions which are connected to the strips of elastic material that provide the elastic means.

7. A mattress ensemble consisting of a mattress, a supporting element upon which the mattress rests and bottom sheet holding means carried by and cooperating with the mattress supporting element, such means comprising a strip of fabric extending adjacent the sides and at least one end of the supporting element and having its lower edge portion attached to the supporting element adjacent its bottom, the strip cooperating with the adjacent vertical faces of the supporting element to provide a continuous externally located pocket for the reception of the

pendant parts of the sheet and of a depth in which said parts may be fitted in flat relation with mitered corners, the strip providing flexible outer walls of the pocket and the vertical faces of the mattress supporting element adjacent the strip providing fixed inner walls of the pocket, the lower edge portion of the strip as attached to the supporting element providing a closed bottom for the pocket, the strip being otherwise unattached to the supporting element, and an endless band of elastic material carried by the strip near its upper edge and normally positioned with its axis in a horizontal plane parallel to the plane of the supporting surface of the mattress, the band being adjacent the vertical faces of the supporting element opposed to the strip and being maintained under tension by the supporting element, the band as maintained under tension by the supporting element being substantially linearly coextensive with the strip, the strip being provided with a continuous sheath open at its ends and in which the band is loosely fitted, the strip and the band being manually pulled laterally away from the supporting element to open the pocket to a suitable extent for the insertion of the pendant parts of the sheet, the strip and the band having a relative sliding action when they are pulled laterally away from the supporting element, the strip having terminal portions which yield relatively to one another when the strip is pulled away from the supporting element, the strip being returned to its state of normal flatness when it is finally released after being pulled away from the supporting element in connection with the making of the bed.

8. A mattress ensemble as set forth in claim 7 wherein the fabric strip substantially circumscribes the mattress supporting element and has its end edges in substantially meeting relation, and the band of elastic material extends across the space between such edges.

WARREN W. ROSING.
